(57) **CLAIM**

We claim the ornamental design for a display screen or portion thereof with animated graphical user interface, as shown and described.

DESCRIPTION

FIG. 1 is a front elevational view of a first image of a display panel or screen with an animated graphical user interface of our design;

FIG. 2 is a front elevational view of a second image thereof; FIG. 3 is a front elevational view of a third image thereof; FIG. 4 is a front elevational view of a fourth image thereof; FIG. 5 is a front elevational view of a fifth image thereof; and,

FIG. 6 is a front elevational view of a sixth image thereof. The appearance of the image transitions sequentially between the images shown in FIGS. 1 to 6. The process or period in which an image transitions to another forms no part of the claimed design.

The broken lines illustrate the display screen or portion thereof and forms no part of the claimed design. The broken lines illustrate portions of the graphical user interface and form no part of the claimed design.
